UNITED STATES PATENT OFFICE.

GEORGE F. SEAVER, OF ASHLAND, MASSACHUSETTS.

IMPROVEMENT IN BOOTS AND SHOES.

Specification forming part of Letters Patent No. 129,989, dated July 30, 1872.

To all whom it may concern:

Be it known that I, GEORGE F. SEAVER, of Ashland, in the county of Middlesex and State of Massachusetts, have invented certain new and useful Improvements in Boots and Shoes, of which the following is a full, clear, and exact description, reference being had to the accompanying drawing making part of this specification, in which—

Figure 1 represents a sectional elevation of a shoe.

This invention consists in the combination of a metal plate, covering nearly or all the surface of the inner sole of a boot or shoe, and placed between the inner and outer soles, with a protecting-plate covering the tip of the outer sole, as specified herein.

The aforesaid protecting-plate *a* is a part of a metal plate, *c*, which covers the whole, or nearly the whole, surface of the inner sole between it and the outer sole, as more fully described in a former application—that is to say, the plate *c* has its forward end extending a sufficient distance or length beyond the forward end of the outer sole to be turned downward and under the outer sole, as in Fig. 1. The plate *a* covers and protects the end of the outer sole or top, and prevents it being worn away, and this protected, preserved, and projecting-forward end of the outer sole or tap

takes all the wear, and prevents wear or injury to the upper-leather at the toe-end *e*; whereas, if the end of the outer sole is unprotected, it is frequently worn off so as to expose and to bring the wear upon the upper-leather, greatly injuring the boot or shoe.

Thus it will be seen that, by protecting and preserving the forward-projecting end of the outer sole or tap, not only this is saved, but also the upper-leather and the whole toe-end of the boot or shoe.

I am aware that hard-metal plates have been applied to the under side of the taps or outer soles of boots and shoes to prevent rapid wear at that point, but such bottom plates do not wholly prevent wear at the end of the sole or tap and untimely exposure and wear of the upper part of the shoe.

I make no claim for the bottom plates or the plates on the under side of the toe-end of the tap or outer sole.

I claim as my invention—

The sole-plate *c*, extended and turned downward to form the tip-protecting plate *a*, substantially as described.

GEO. F. SEAVER.
